CODED TRACK CIRCUIT SYSTEM OF RAILWAY SIGNALING

Leslie R. Allison, Forest Hills, Pa., assignor to The Union Switch & Signal Company, Swissvale, Pa., a corporation of Pennsylvania

Application April 3, 1941, Serial No. 386,615

8 Claims. (Cl. 246—33)

My invention relates to coded track circuit systems of railway signaling and it has special reference to A. P. B. and other two-direction running systems of this character wherein use is made of the "coded feed back" operating principle that first was disclosed by Frank H. Nicholson Patent No. 2,021,944 (issued November 26, 1935) and that also is shown by numerous later patents and applications of common ownership herewith.

Generally stated the object of my invention is to overcome a reset difficulty which is experienced with "coded feed back" track circuit combinations when they are included in A. P. B. systems of the combined "master-feed back-special" code energy type which the following copending applications disclose and claim: Serial No. 294,897, filed September 14, 1939, by Ralph R. Kemmerer; Serial No. 382,431, filed March 8, 1941, by Frank H. Nicholson; and Serial No. 386,642, filed April 3, 1941, by Ralph R. Kemmerer and Crawford E. Staples.

A more specific object is to increase the effectiveness of track circuit reset facilities of the code period interchange type which Robert M. Gilson application Serial No. 386,642 (filed April 3, 1941) discloses and claims.

Another object is to utilize the Gilson principle of code period interchange for preventing A. P. B. systems of the "master-feed back-special" code type above named from "cascading" a reset operation requirement back and forth from one end of the A. P. B. stretch to the other.

In practicing my invention I attain the above and other objects and advantages by: (1) supplementing the code supply apparatus at one end of each track section in the A. P. B. stretch by an auxiliary device which when operated interchanges the "on" and "off" periods of the coded energy which is supplied to the section rails at the device location; and (2) arranging that this device will delayedly operate in response to each restoration of the adjoining track section to its normal "coded feed back" form of vacant section operation.

I shall describe an A. P. B. system track circuit organization which embodies my invention, and shall then point out the novel features thereof in claims. This illustrative embodiment is disclosed in the accompanying drawings in which:

Fig. 1 is a diagrammatic showing of the anti-cascade reset improvements of my invention applied to a "coded feed back" track circuit combination which is organized as in the earlier re-

ferred to Nicholson application Serial No. 382,431;

Fig. 2 illustrates the various forms of coded energy which are effective in the track circuit combination of Fig. 1 before, during and after my new apparatus functions to effect a reset of the combination; and

Fig. 3 is a fragmentary showing of the reset apparatus of Fig. 1 modified to make use of a code period shifting device which is energized over a back instead of a front contact of the relay that responds to restoration of the adjacent track section to the normal "coded feed back" form of vacant section operation.

In the several views of the drawings like reference characters designate corresponding parts. Referring first to Fig. 1, I have there reproduced, in a form modified as to certain details, one of the track circuit combinations of the A. P. B. system which Nicholson application Serial No. 382,431 discloses and claims.

Track circuit combination of Fig. 1

The track section to which the Nicholson structure of Fig. 1 is applied forms part of the usual siding-to-siding A. P. B. stretch (not completely shown in Fig. 1 hereof) of two-direction running track 1—2 and it includes the portion of that stretch which is between intermediate locations II and III. This section is equipped with the usual wayside signals SEII and SWIII by which the entry of eastbound and of westbound traffic into the section is respectively governed. These two signals, in turn, are controlled through the medium of two coded track circuits which are reversely arranged and which operate (under vacant track stretch conditions) on the "coded feed back" principle of the earlier mentioned Nicholson Patent No. 2,021,944.

When organized into a complete A. P. B. system of the non-line-wire character which the earlier identified Nicholson application discloses and claims, these two reversely arranged track circuits cooperate with corresponding facilities of adjoining track sections (not completely illustrated herein) in a manner enabling each train that enters the A. P. B. stretch to establish both directional and following protection without the aid of line wires for signal control purposes.

The non-line-wire A. P. B. system from which the track circuit combination of Fig. 1 has been reproduced is broadly similar to that of the Nicholson application and differs therefrom only by minor changes in system arrangement and individual element design. These differences

are of detail rather than of principle and will, it is thought, become evident from the following description of the Fig. 1 track section II-III and the apparatus directly associated therewith.

In this track circuit organization of Fig. 1, the "master" energy source BX-CX is at the section west end II and it transmits "on" period pulses of master code energy to a master track relay TR at the section east end; the "feed back" energy source BK-CK is at that east end III and it transmits "off" period pulses of feed back energy to a feed back track relay TRA at the section west end; the westbound wayside signal SWIII is controlled by the master track relay TR through the medium of "home" and "distant" decoding relays HW and DW; and the eastbound wayside signal SEII is controlled by the feed back track relay TRA through the medium of corresponding decoding relays HE and DE.

Each set of these decoding relays HW-DW and HE-DE is supplied with pick-up energy over a pole changing contact 7 of the associated track relay and the two relays of the set have the usual "frequency code" form of response characteristics. That is, both relays in each set stay released when the controlling track relay (TR or TRA) fails to follow code; the "home" relay (HW or HE) picks up whenever the controlling track relay follows code of either a 75 or a 180 pulse per minute frequency; and the "distant" relay (DW or HW) picks up only when the controlling track relay follows code of the 180 pulse per minute frequency.

This selective response by the "distant" relays DW and DE is produced by frequency selective units 180DU interposed in the relay energizing circuits in the usual manner. The necessary rectification of the current which the decoding transformers DTW and DTE supply to the "home" relays HW and HE is effected by track relay contacts 4 arranged as disclosed and claimed by a copending application Serial No. 210,744, filed May 28, 1938, by Frank H. Nicholson et al., now U. S. Letters Patent 2,237,788, granted April 8, 1941.

The indication which westbound signal SWIII displays is determined by east-end decoding relays HW-DW through the medium of contacts 18-19 and the indication displayed by eastbound signal SEII is similarly controlled by west-end decoding relays HE-DE. In each instance the controlled signal shows: (1) "clear" when the associated track relay (TR or TRA) follows code at the 180 rate; (2) "approach" when the track relay follows code at the 75 rate; and (3) "stop" when the track relay fails to follow code.

Coding of the "master" energy that is supplied to the section at west location II is effected by a repeater relay CP through the medium of contacts 110-111. When picked up these contacts connect (through transformer TTW) the section rails 1-2 with source BX-CX and thereby produce a master code "on" period; when released these contacts transfer the rail connection to track relay TRA and thereby produce a master code "off" period.

Serving to drive this repeater relay CP are a pair of code transmitters 180CT and 75CT installed at location II and provided with contacts 180 and 75 which pick up and release at the respective frequencies of 180 and 75 times per minute. Selection of which of these contacts is included in the repeater relay driving circuit is made by a contact 112 of the westbound decoding relay HW for the next track section to

the west. When picked up (as shown) this contact assigns the driving circuit (conductor 25) to transmitter contact 180 and thereby causes relay CP to produce a master energy code consisting of 180 "on" period pulses per minute; when released contact 112 transfers the driving circuit to transmitter contact 75 and thereby causes (when a "knockdown" contact 114 of a west bound directional stick relay WS is picked up) relay CP to produce a master energy code consisting of 75 "on" period pulses per minute.

In flowing eastwardly over the section rails to east location III the recurring pulses of this master code energy (from source BX-CX) are impressed upon the master track relay TR by way of transformer TTE, back contacts 116-117 of an impulse relay RC, and a rectifier 118. Under vacant section conditions, accordingly, this track relay TR is caused to pick up and release its contacts 7-4 in step with the operations of code producing contacts 110-111 of the west end relay CP. By the associated decoding relays HW-DW that response is, in turn, translated into appropriate indication selections for the westbound wayside signal SWIII.

The "master" track circuit organization of Fig. 1 is, therefore, effective to control the westbound signals SW in the usual automatic block system manner and when expanded into a complete A. P. B. system it thus provides the desired following protection for all westbound train moves through the A. P. B. stretch.

For contributing to a corresponding control of the eastbound wayside signals SE use is made of "feed back" track circuit apparatus earlier referred to as supplementing the "master" organization just described. As already stated, this apparatus includes the track relay TRA at the section west end II and the trackway source BK-CK at the section east end III. During the "off" periods of the east-end received master code energy, the before mentioned impulse relay RC connects this source with the section rails over the front points of its contacts 116-117 and thereby supplies the rails with the pulsed feed back energy by which the west end track relay TRA is operated.

Both in function and in operation this impulse relay RC closely resembles a device which Herman G. Blosser Reissue Patent No. 21,783 (granted April 29, 1941) discloses at IR in a "coded feed back" track circuit combination for single direction running. When this relay RC is deenergized contacts 116-117 thereof occupy the released position (shown in Fig. 1) wherein the section rails are connected with the master track relay TR; when, however, suitable pick-up current is supplied to the relay these contacts pick up and transfer the rail connection to the feed back source BK-CK.

Under vacant conditions of section II-III, this pick-up current is derived from an output winding 120 of the decoding transformer DTW and transmitted to relay RC through a transformer 121. The primary of this transformer is connected with winding 120 over either a front contact 122 of the eastbound decoding relay HE for the next section to the east or the back point of contact 122 in series with a contact 123 of an eastbound directional stick relay ES; the secondary of this transformer 121 is connected with the winding of relay RC over a front contact 125 of westbound decoding relay HW and a back contact 126 of the westbound directional stick relay WS at location III.

Relay RC responds only to "positive" polarity pick-up energy (which makes the right terminal of its winding positive with respect to the left terminal) and each release of the master track relay TR causes decoding transformer DTW to induce in winding 120 a pulse of such positive polarity potential. When the just described primary and secondary circuits for transformer 121 are both complete, each of those positive pulses is transmitted to relay RC and produces a momentary pick-up on the part of contacts 116-117 thereof. Such pick-up, as already pointed out, connects the section rails with east end source BK-CK and causes a short pulse of feed back energy to be supplied thereto.

Under the conditions just described, each of these pulses coincides with an "off" period of the west end supplied master code and hence is transmitted over the section rails to west location II and there impressed upon the feed back track relay TRA through transformer TTW, back contacts 110-111 of device CP and a rectifier 130. This west end track relay TRA is, in consequence, caused to pick up its contacts 1-4 in step with the "off" period pick-ups of the east end impulse relay RC. By the associated decoding relays HE-DE that response is, in turn, translated into appropriate indication selections for the east-bound signal SEII.

For the purpose of equalizing the pick-up and release times of the so operated feed back track relay TRA, its pick-up circuit is supplemented by a stick circuit which prolongs each of the relay pick-ups for the full duration of the "off" period during which the pick-up occurs. This stick circuit includes a back contact 133 of the master coder relay CP and a front contact 134 of the track relay; it is supplied with energy over either a front contact 135 of the westbound decoding relay HW for the next section to the west or the back point of contact 135 and a front contact 136 of the westbound directional stick relay WS at location II; and it operates in the same manner as that disclosed and claimed by Patent No. 2,172,893 which issued to Edward U. Thomas on September 12, 1939.

Under other conditions (which will be made more evident presently) the east end relay RC operates not as an impulse device for the supply of "feed back" pulses during the master code "off" periods but instead as a repeater for one or another of the code transmitters 180CT and 15CT at location III. Under these other conditions the energy supplied from source BK-CK over front contacts 116-117 is modulated independently of the master code pulses from west location II. To designate this independently modulated energy the term "special code" will be employed.

During these just referred to other conditions, a driving circuit for relay RC is set up over back contacts 126 and 125 of relay WS and HW. This driving circuit has much in common with certain corresponding control paths that an application Serial No. 315,801 filed by Crawford E. Staples on January 26, 1940, now U. S. Patent 2,244,901, granted June 10, 1941, discloses for headblock location devices KR. It includes a selector contact 138 of the eastbound decoding relay HE for the track section to the east of location III. When picked up this contact assigns the driving circuit to the back point of the code transmitter contact 180 at the same location; when released it transfers the circuit connection to the back point of the code transmitter con-

tact 15 over a path that includes a front contact 139 of the eastbound stick relay ES.

Comparing the sets of code transmitters CT which are shown at the two locations II and III it will be noted that at each location the back point connections which the preceding paragraph describes (see location III) may be to the same contacts 180 and 15 as are the front point connections earlier described for the "master" coder relay driving circuits (see location II) at the same location.

The above mentioned relays ES and WS are directional stick devices of the character ordinarily used in two direction running systems of A. P. B. signal control. One set of these relays ES-WS is provided at each of the two ends II and III of the Fig. 1 track circuit and control there-of may be over local energizing circuits (not here shown) equivalent to those which the earlier named Kemmerer application Serial No. 294,897 shows and describes.

When arranged in that customary A. P. B. manner both of the relays in each ES-WS set will be deenergized and stay released (as shown in Fig. 1 of the present application) as long as the A. P. B. stretch of single track remains vacant. Upon movement of a westbound train through the stretch the normally released westbound relay WS at a given intermediate location will pick up when the leading vehicle of the westbound train first passes that location and so stay until the trailing vehicle of the train clears the west end of the section of which the given location marks the east end. Similarly, upon movement of an eastbound train through the stretch, the normally released eastbound relay ES at a given intermediate location will be picked up only from the time that the leading vehicle of the eastbound train first passes that location until the trailing vehicle of the train has cleared the east end of the track section to the immediate east of the location.

When the A. P. B. stretch of which the Fig. 1 track section II-III is assumed to form a part is vacant throughout its entire length, it will thus be seen that the "off" periods of the west end supplied master code recur at the 180 frequency rate; that the feed back relay TRA at location II is by "off" period energy received from the section east end caused to follow code at the same rate; and that the associated relays HE-DE ordinarily would set the signal SEII at "clear." For a purpose which need not here be considered, however, the pick-up circuit for "distant" relay DE is broken, under these conditions, by a contact 131 of the westbound decoding relay HW at location II.

Signal SEII is, in consequence, normally held at "approach." This holding, however, does not interfere with the desired "clear" showing upon the approach of an eastbound train. Upon such approach the west bound decoding relay HW (at location II) for the next section to the west releases and restores (at contact 131) the control of eastbound decoding relay DE to track relay TRA. The westbound stick relay WS at location II also is released and in consequence the master coder relay CP at the same location is maintained (at contacts 112-114) continuously deenergized.

This deenergization keeps (at back contacts 110-111) the west end track relay TRA continuously connected with the rails of section II-III, removes all "master" code energy therefrom, effects the release of westbound decoding relays HW-DW at location III, and there causes

contact 125 to assign the control of impulse relay RC to one or the other of the east end code transmitters 180CT and 75CT. Under vacant conditions of the track section to the east, relay HE at location III will be picked up and contact 138 thereof now will assign the impulse relay driving circuit to the back point of transmitter contact 180.

This assignment causes relay RC recurrently to pick up at the frequency of 180 times per minute and thus supplies section II-III with "special code" energy (from east end source BK-CK) in the form of pulses that recur at the frequency of 180 per minute. In being received at the west location II these special code pulses operate track relay TRA and thereby pick up both of the decoding relays HE-DE. In consequence the eastbound wayside signal SEII now shows "clear."

Should the track section to the east of location III be occupied by an advance east bound train the indication displayed by signal SEII will be "approach" instead of "clear." This comes about as follows. The following train in the section to the west of location II still acts through relays WS and HW at that location to keep (at contacts 112-114) the master coder relay CP continuously released and the track relay TRA continuously connected with the rails of section II-III. This continues the released condition of relays HW-DW at location III and there keeps (at contact 125) the driving circuit for the relay RC assigned to the code transmitter CT.

Meanwhile, the advance train in the section to the east of location III keeps relay HE thereat released and causes the eastbound stick relay ES at the same location to stay picked up. Contact 138 of relay HE now assigns (over front contact 139 of relay ES) the impulse relay driving circuit to the back point of code transmitter contact 75. This assignment causes relay RC recurrently to pick up at the frequency of 75 times per minute and thus supplies the section rails with "special code" energy (from east end source BK-CK) of the 75 pulses per minute variety. In being received at location II this special 75 code energy operates track relay TRA and thereby causes eastbound signal SEII to show "approach," as aforesaid.

Should, finally, the advance train be in section II-III, the eastbound signal SEII will display "stop." This, of course, results from the usual deenergization of track relay TRA and the consequent release of both of the eastbound decoding relays HE-DE at location II.

The combined "feed back" and "special code" track circuit organization which has just been described in connection with Fig. 1 is, therefore, effective to control the eastbound signals SE in the usual automatic block system manner and when expanded into a complete A. P. B. system it thus provides the desired following protection for all eastbound train moves through the A. P. B. stretch.

Such a complete A. P. B. system will, quite obviously, also offer all of the usual features of directional protection signal control. Since these do not form a part of the present invention, detailed description thereof will not here be given. It may, instead, be said that: (1) in the provision of westbound directional protection use is made of "knockdown" contacts 123 carried by the eastbound stick relays ES and arranged to prevent the westwardly extending sections from receiving "feed back" energy (from source BK-CK)

during passage of westbound traffic through the stretch; and (2) in the provision of eastbound directional protection use is made of other "knockdown" contacts 114 carried by the westbound stick relays WS and arranged to prevent the eastwardly extending sections from receiving "master" 75 code energy (from source BX-CX) during the passage of eastbound traffic through the stretch.

The reset problems of Fig. 1

The problems of reset which the A. P. B. system combination of Fig. 1 presents have much in common with those with which the earlier referred to Gilson application Serial No. 386,642 deals. That application is directed to the provision of means for effecting an "initial" reset of each A. P. B. system track circuit under certain conditions wherein the two ends of the circuited section are supplied with "master" and "special" code energy pulses which coincide with and hence directly oppose each other.

In the case of the track section which Fig. 1 shows at II-III, such conditions exist when the west end supplied (from source BX-CX) pulses of "master" code energy recur at the same frequency as and directly coincide with the opposing pulses of east end supplied (from source BK-CK) "special" code energy. Under those conditions the west end supplied pulses of master energy may have the character shown at "master 180 (original)" in Fig. 2 and the east end supplied pulses of special energy may have the directly coinciding character which is shown at "special 180" in Fig. 2.

It is true that the west end and the east end coding devices CT180 by which these master and special codes are produced operate independently of one another, yet it also frequently happens that contacts 180 of device CT at location III may get and stay in exact synchronism with contacts 180 of device CT at location II. In that event, quite obviously, each pulse of west-to-east flowing master energy is met and directly opposed by a pulse of east-to-west flowing special code energy.

As long as this condition exists, the master and feed back track relays TR and TRA at locations III and II are both prevented from receiving energy from the opposite ends of the section. The resulting continuous release of relay TR at location III causes the associated device HW to continue (at contact 125) the supply of special code energy and to prevent the feed back apparatus from being brought into action. This opposing pulse interference, moreover, keeps the westbound and the eastbound signals SWIII and SEII at "stop" even though the section II-III may be completely vacant.

To overcome the condition just stated, the Gilson application supplements the code supply apparatus at one end of each circuited section by a code converter relay CCR (not shown herein) which during and immediately following each shunt of the section rails recurrently interchanges the "on" and "off" periods of the coded energy which is impressed upon those rails at the converter location. Upon restoration of the section to its normal unshunted condition, this interchange disrupts any reset preventing coincidence of the "master" code energy pulses and the opposing (and still independently supplied) pulses of "special" code energy and thereby permits the master energy pulses to reach the master track relay at the feed back section end.

In responding in the usual manner that relay now discontinues the special code energy, substitutes "off" period pulses of "feed back energy" therefor and thereby restores the track circuit to the desired "coded feed back" form of vacant section operation.

My present invention concerns itself with the effect on a particular section of actions which take place in one of the adjoining sections of the A. P. B. stretch. This effect is to be distinguished from the problems of "initial" reset with which the Gilson application deals and it results in what will be termed a "cascading" of the reset operation requirement from one section to another.

The resulting problem of reset cascading results from the fact that A. P. B. systems which include track circuits of the Fig. 1 (hereof) type are found to transfer from one section to another certain reset requiring conditions. Laboratory tests, moreover, demonstrate that this cycling of the reset operation requirement may in certain cases be "cascaded" back and forth from one end of the A. P. B. stretch to the other several times before permanent reset is effected.

In the A. P. B. system which the diagram of Fig. 1 partially represents, this phenomena of reset operation cascading may be produced in the following manner. If, with the entire A. P. B. stretch initially vacant, the rails of the section to the immediate west of location II are subjected to a shunt the westbound code detector relay HW (at location II) for that west section releases. That release opens (at contacts 112 and 114 of devices HW and WS) the driving circuit for master coder relay CP at location II and thereby removes all master code energy from the rails of section II-III.

At the east location III, in consequence, master track relay TR becomes continuously de-energized and releases device HW. That release assigns (at contact 125) the driving circuit for impulse relay RC to contact 180 of east end code transmitter 180CT and thus causes the rails of section II-III to be supplied with special code energy of the 180 pulse per minute variety.

When, now, the shunt is removed from the section to the west of location II and the track circuit for that section initially resets (as by aid of a code converter relay of Gilson's CCR type—not here shown) the resulting pick-up of relay HW at location II restores the control of the master coder relay CP to west end transmitter 180CT. In consequence the rails of section II-III now once more are supplied with master code energy of the 180 pulse per minute variety.

Quite obviously, now, section II-III must go through the before explained operations of reset before the normal "coded feed back" form of vacant section operation can be restored thereto.

At the east location III, meanwhile, the release of relay HW which accompanies the requirement for reset by section II-III affects the track section to the immediate east by breaking the driving circuit of relay CP (not shown) therefor and thereby removing all master energy from the rails of that east section. Upon reset of section II-III and the resulting pick-up of relay HW at location III, in consequence, the just described reset requiring conditions are transferred to the track section to east of location III.

In the manner just set forth, accordingly, the requirement for track circuit reset may be pro-

gressively transferred from section to section in the direction of from west to east.

Under certain further conditions, moreover, a similar progressive transfer or "cascading" of the reset requirement also may take place in the opposite or east-to-west direction. One manner in which this might come about will now be described.

Upon removal of a shunt therefrom, section II-III of Fig. 1 may initially reset in one of the manners earlier explained; the resulting pick-up of relay HE at location II then effects an immediate reset of the section to the west of that location and thereby causes succeeding sections to the west similarly to reset; and the accompanying pick-up of relay HW at location III then assigns the control of the there located coder relay RC to transmitter 180CT.

If in the section to the immediate east of location III a "clashing" of opposing code pulses now occurs, reset of the track circuit for that section will be delayed. Because of this delay relay HE at location III now drops and by de-energizing (at contact 122) relay RC at the same location removes BK-CK energy from the rails of II-III and thereby effects the release of relay HE at location II. Section II-III now has, in consequence, lost its "initial" reset.

The "reset loss" action just described may, moreover, repeat itself into successive track sections to the west of location II. As a result, quite obviously, the requirement for track circuit reset also may be progressively transferred from section to section in the direction of from east to west.

Under the above stated and certain other conditions not herein described, a requirement for track circuit reset thus may cascade itself in either direction throughout the entire length of the A. P. B. stretch. The earlier mentioned laboratory tests confirm that such cascading is more than a mere possibility; it, in reality, constitutes a serious obstacle to the successful operation of coded A. P. B. systems of the type herein considered.

The reset apparatus of Fig. 1

To overcome the "cascading" difficulty just stated, I propose to use apparatus which may supplement either the special code pulse supply equipment at the feed back end of each section or the master code energy supply equipment at the master section end. At either location this apparatus takes the form of an auxiliary relay which upon restoration of the adjacent track circuit to its normal "coded feed back" vacant section operation delayedly interchanges the "on" and the "off" periods of the there supplied code and thus disrupts any reset preventing coincidence of the master and special code energy pulses.

That disrupting action effectively assures that the master code energy will reach the track relay TR at the feed back end of the section. By responding in the usual manner, that relay now discontinues the special code energy, substitutes "off" period pulses of feed back energy therefor and thereby restores the section to its normal "coded feed back" form of vacant section operation. This restoration is progressively duplicated by successive adjoining sections wherein the requirements for reset may have been set up.

In the embodiment of my invention which is shown for section II-III of Fig. 1, this auxiliary relay takes the form of a device FL installed as

shown at the master supply location II and energized over a front contact 101 of the westbound code detecting relay HW for the next track section to the west. This relay FL is provided with a contact 100 that is included in the driving circuit for the coder relay CP which modulates the master energy that is supplied to the east end of section II-III.

Under picked up conditions of relay FL, this contact 100 connects (as shown) the CP driving circuit with the front point of contact 180 of the code transmitter 180CT at location II; when, however, relay FL is released, contact 100 transfers the named connection to the back point of a companion contact 180a of the same transmitter. Each shift, therefore, in the position of contact 100 causes the coder relay CP to interchange the "on" and the "off" periods of the master code energy which is supplied to the west end of section II-III.

Current for energizing this relay FL is supplied to the winding thereof over the front point of a contact 101 which is carried by the westbound decoding relay HW for the next section to the west of location II. As long, accordingly, as that west section relay HW is picked up, relay FL holds contact 100 also picked up; when, however, the controlling relay HW releases, contact 101 breaks the energizing circuit for relay FL and allows contact 100 also to release. For a purpose to become more evident presently, this contact 100 of relay FL is given a short period of pick-up delay.

In examining how the reset facilities of Fig. 1 operate, let it be assumed that the track circuit combination of that figure is included in a multi-section stretch of A. P. B. track and that each section in that stretch is equipped with apparatus which duplicates the equipment of Fig. 1.

Under vacant conditions of that entire stretch all of the track circuit combinations therein are operating in the normal "coded feed back" manner; the eastbound and the westbound decoding relays HE and HW for each of the circuited sections are picked up; and the pulse-shifting relay FL for each section thus also is picked up.

Assume now that an eastbound train comes into the section which is to the immediate west of location II. At that location this train effects the release of relay HW and thereby causes: (1) relay FL to release contact 100; and (2) relay CP to be disconnected (at contacts 112-114) from both of the code transmitters 180CT-75CT. That relay CP now discontinues the supply of master code energy to the west end II of section II-III and thus continuously releases the track relay TR at the section east end III.

The resulting release of relay HW at location III assigns (at contact 125) the control of impulse relay RC to code transmitter 180CT at the same location and thereby causes the rails of section II-III to be supplied with "special code" energy of the 180 pulse per minute character. This energy flows westwardly and operates track relay TRA at location II.

Assume next that the eastbound train leaves the section to the west of location II by way of an intermediate spur siding (not shown). Following this removal of section rail shunt, the track section for that west section initially resets (as by aid of a code converter relay of Gilson's before mentioned CCR type—not here shown) and the resulting pick-up of relay HW at loca-

tion II: (1) completes (at contact 101) the energizing circuit for relay FL; and (2) connects (at contact 112) the driving circuit for relay CP with code transmitter 180CT. That connection causes master code energy of the 180 pulse per minute variety to be supplied to the west end of section II-III.

This energy tries to flow eastwardly to track relay TR at location III but is opposed by the there supplied pulses of 180 special code energy. If the timing happens to be such that the pulses of the opposing codes interfit, relay TR is immediately energized and by picking up relay HW at location III it transfers (at contact 125) the driving circuit of relay RC from code transmitter 180CT to winding 120 of decoding transformer DTW. In that event section II-III is without delay restored to the desired "coded feed back" form of vacant section operation.

Meanwhile, relay FL at location II picks up (at the end of its period of response delay) and transfers (at contact 100) the driving connection for master coder relay CP from the back point of transmitter contact 180a to the front point of transmitter contact 180. The track circuit already having reset, however, the resulting interchange of master code "on" and "off" periods does not disturb the "coded feed back" form of vacant section operation.

In the event, however, that the pulses of west-end-supplied master 180 code initially do coincide (see the upper portion of Fig. 2) with the pulses of east-end-supplied special 180 code, then both of the track relays TR and TRA are deprived of operating energy and the desired reset of the track circuit is delayed. This delay continues only until relay FL at location II picks up. Upon that happening, the resulting interchange of the master code "on" and "off" periods sets up the interfitting relation of opposing energy pulses which the lower portion of Fig. 2 represents.

Each of the track relays TR and TRA now does receive operating energy from the section rails, the resulting code following action of relay TR picks up westbound decoding relay HW at location III, that pick-up transfers (at contact 125) the driving circuit for impulse relay RC from code transmitter 180CT to winding 120 of decoding transformer DTW, and that transfer restores the track circuit combination to the desired "coded feed back" form of vacant section operation.

In order that the reset action just described may take place in the best and most effective manner possible, the period of pick-up delay for contact 100 of relay FL is made sufficiently long to allow the westbound decoding relay HW at the section east end to pick up before relay FL responds if the code transmitters 180CT at the two section ends initially are out of step but not long enough to permit the eastbound decoding relay HE at the section west end to release before relay FL responds should the two code transmitters 180CT initially be in step. When the decoding relays HW-HE have response characteristics of one order now very commonly used, a period of pick-up delay of about two-thirds of a second is found to be satisfactory for relay FL.

Use of reset apparatus of the just described Fig. 1 type is found to safeguard adjoining track sections in a vacant A. P. B. stretch from having their "coded feed back" form of operation objectionably interfered with and thus it effectively prevents any original reset requirement from be-

ing cascaded back and forth through the A. P. B. stretch before permanent reset is effected.

The reset facilities of Fig. 3

In Fig. 3 I have shown reset facilities which differ from those of Fig. 1 only through a substitution for slow pick-up relay FL of a slow release pulse-shifting relay BL. This relay BL is energized over the back point of contact 101 of the westbound decoding relay HW for the next track section to the west. The contact 100 thereof is included in the driving circuit (contact 112 and conductor 25) for the master coder relay CP (not shown in Fig. 3) at the relay location. This contact 100 has a period of release delay which is of the same magnitude as is the pick-up delay period for contact 100 of the earlier described relay FL of Fig. 1.

In explaining how the reset facilities of Fig. 3 operate, assume that the complete track circuit combination of Fig. 1 has relay FL thereof replaced by device BL of Fig. 3. Under vacant conditions of the A. P. B. stretch of which track section II-III forms a part, relay HW at location II is picked up, code-shifting relay BL is released, and contact 100 connects the master coder (device CP) driving circuit with the back point of the code transmitter contact 180a.

As, now, an eastbound train enters the track section to the immediate west of location II, relay HW at that location releases and thereby: (1) picks up (over contact 101) relay BL; and (2) disconnects (at contacts 112-114) the driving circuit of master coder relay CP from both of the code transmitters 180CT-75CT.

Should this eastbound train now move out of the section to the west of location II by way of an intermediate passing siding, there will result in section II-III a series of actions which are identical with those earlier described for Fig. 1 with but a single exception. This exception is that the initial pick-up of decoding relay HW at location II is responded to by a delayed release of contact 100 of relay BL instead of a delayed pick-up of contact 100 of relay FL.

That delayed release assures prompt reset of the track section in exactly the same manner as has already been explained for the reset facilities of Fig. 1. Because of this identity, further detailed description of how the Fig. 3 apparatus operates is not believed to be necessary.

Summary

Although the reset cascade prevention facilities of my invention are herein shown and described as being used with "coded feed back" track circuit combinations of only one A. P. B. system form (Fig. 1), it will be obvious that such use is illustrative rather than restrictive and that my new cascade prevention facilities will also have utility with and hence may be applied to signaling system control circuit combinations of still further forms wherein a condition of opposing code pulse coincidence may at times be transferred from one circuit combination to another.

From the foregoing, accordingly, it will be seen that I have made important contributions to coded track circuit systems of two-direction signaling. In particular I have overcome a reset difficulty which is experienced with "coded feed back" track circuit combinations when they are included in A. P. B. systems of the combined "master-feed back-special" code type hereinbefore described; I have increased the effectiveness of track circuit reset facilities of the code period

interchange type which Robert M. Gilson application Serial No. 386,642 discloses and claims; and I have utilized the Gilson principle of code period interchange for preventing A. P. B. systems of the "coded feed back" track circuit type from "cascading" a reset requirement back and forth from one end of the A. P. B. stretch to the other.

Although I have herein shown and described only two forms (Figs. 1 and 3) which apparatus embodying my invention may take, it is understood that various changes and modifications may be made in that apparatus within the scope of the appended claims without departing from the spirit and scope of my invention.

Having thus described my invention, what I claim is:

1. In combination, a stretch of two-direction running railway track, adjoining first and second track sections included in said stretch, master code equipment located at the junction of said first and second sections and effective to supply the second section rails with master code energy in the form of recurring "on" period pulses that are separated by "off" period intervals, feed back apparatus located at the remote end of said second section and operable when and only when said master code pulses are there received further to supply the second section rails with feed back energy in the form of pulses that recur in step with the "off" periods of the received master code, supplemental equipment also at the remote end of said second section which comes into operation only when said feed back equipment is maintained inactive by failure of said master energy to reach the equipment location and which then supplies the second section rails with special code energy in the form of recurring pulses that have no regular time coincidence with the aforesaid master code "off" periods, means for maintaining said second section master code equipment inactive under shunted conditions of the rails of said first section, and means effective upon removal of a shunt from said first section rails for delayedly interchanging the "on" and the "off" periods of said second section master code whereby to disrupt any vacant section coincidence of said special code and master energy pulses that may have prevented those master pulses from earlier reaching said second section remote end and there restoring said feed back apparatus to its normal condition of vacant section operation.

2. In combination, a stretch of two-direction running railway track, adjoining first and second track sections included in said stretch, master equipment at the junction of said two sections operated by a master coding contact over a driving connection therewith and effective to supply the rails of said second section with master code energy in the form of recurring "on" period pulses that are separated by "off" period intervals, feed back apparatus at the remote end of said second section driven by the there received pulses of said master code energy and operable during and only during said master pulse reception further to supply the second section rails with feed back energy in the form of pulses that recur in step with the "off" periods of the received master code, supplemental equipment also at said second section remote end operated by an independent coding contact over a driving connection herewith and effective only when said feed back apparatus is maintained inactive by failure of said master energy to reach the equipment loca-

tion still further to supply the second section rails with special code energy in the form of recurring pulses that have no regular time coincidence with the aforesaid master code "off" periods, means for maintaining said second section master code equipment inactive under shunted conditions of the rails of said first section, and means effective upon removal of a shunt from said first section rails for delayedly interchanging the "on" and the "off" periods of said second section master code whereby to disrupt any vacant section coincidence of said special code and master energy pulses that may have prevented those master pulses from earlier reaching said second section remote end and there restoring said feed back apparatus to its normal condition of vacant section operation.

3. In combination, a stretch of two-direction running railway track, a track section included in said stretch, master equipment at a given end of said section operated by a master coding device over a driving connection therewith and effective to supply the section rails with master code energy in the form of recurring "on" period pulses that are separated by "off" period intervals, feed back apparatus at the opposite end of said section driven by the there received pulses of said master code energy and operable during and only during said master pulse reception further to supply the section rails with feed back energy in the form of pulses that recur in step with the "off" periods of the received master code, supplemental equipment also at said opposite section end operated by an independent coding device over a driving connection therewith and effective only when said feed back apparatus is maintained inactive by failure of said master energy to reach the equipment location still further to supply the section rails with special code energy in the form of recurring pulses that have no regular time coincidence with the aforesaid master code "off" periods, a relay at one of said two section ends which delayedly responds to predetermined changes in the traffic conditions of said stretch, and means rendered effective by each of said relay responses for shifting the said equipment driving connection at the relay location from a first to an opposed contact point of the associated coding device whereby to interchange the "on" and the "off" periods of the said coded energy that said device driven equipment supplies and thereby disrupt any vacant section coincidence of said special code and master energy pulses that may have prevented those master pulses from earlier reaching said opposite section end and there restoring said feed back apparatus to its normal condition of vacant section operation.

4. In combination, a stretch of two-direction running railway track, a track section included in said stretch, master equipment at a given end of said section operated by a master coding device over a driving connection therewith and effective to supply the section rails with master code energy in the form of recurring "on" period pulses that are separated by "off" period intervals, feed back apparatus at the opposite end of said section driven by the there received pulses of said master code energy and operable during and only during said master pulse reception further to supply the section rails with feed back energy in the form of pulses that recur in step with the "off" periods of the received master code, supplemental equipment also at said opposite section end which is operable only when said

feed back apparatus is maintained inactive by failure of said master energy to reach the equipment location and which then supplies the section rails with special code energy in the form of recurring pulses that have no regular time coincidence with the aforesaid master code "off" periods, a relay at said given section end which delayedly responds to predetermined changes in the traffic conditions of said stretch, and means rendered effective by each of said relay responses for shifting the said master equipment driving connection from a first to an opposed contact point of said master coding device whereby to interchange said master code "on" and "off" periods and thereby disrupt any vacant section coincidence of said special code and master energy pulses that may have prevented those master pulses from earlier reaching said opposite section end and there restoring said feed back apparatus to its normal condition of vacant section operation.

5. In combination, a stretch of two-direction running railway track, a track section included in said stretch, master equipment at a given end of said section operated by a master coding device over a driving connection therewith and effective to supply the section rails with master code energy in the form of recurring "on" period pulses that are separated by "off" period intervals, feed back apparatus at the opposite end of said section driven by the there received pulses of said master code energy and operable during and only during said master pulse reception further to supply the section rails with feed back energy in the form of pulses that recur in step with the "off" periods of the received master code, supplemental equipment also at said opposite section end operated by an independent coding contact over a driving connection therewith and effective only when said feed back apparatus is maintained inactive by failure of said master energy to reach the equipment location still further to supply the section rails with special code energy in the form of recurring pulses that have no regular time coincidence with the aforesaid master code "off" periods, an auxiliary relay at one of said two section ends which is released during certain traffic conditions in said stretch and which picks up a short time following a predetermined change in those conditions, and means rendered effective by each of said relay pick-ups for shifting the said master equipment driving connection at the relay location from a first to an opposed contact point of said master coding device whereby to interchange the "on" and the "off" periods of the said master code energy that said contact driven equipment supplies and thereby disrupt any vacant section coincidence of said special code and master energy pulses that may have prevented those master pulses from earlier reaching said opposite section end and there restoring said feed back apparatus to its normal condition of vacant section operation.

6. In combination a stretch of two-direction running railway track, a track section included in said stretch, master equipment at a given end of said section operated by a master coding device over a driving connection with a contact thereof and effective to supply the section rails with master code energy in the form of recurring "on" period pulses that are separated by "off" period intervals, feed back apparatus at the opposite end of said section driven by the there received pulses of said master code energy and operable during and only during said master

pulse reception further to supply the section rails with feed back energy in the form of pulses that recur in step with the "off" periods of the received master code, supplemental equipment also at said opposite section end operated by an independent coding contact over a driving connection therewith and effective only when said feed back apparatus is maintained inactive by failure of said master energy to reach the equipment location still further to supply the section rails with special code energy in the form of recurring pulses that have no regular time coincidence with the aforesaid master code "off" periods, an auxiliary relay at one of said two section ends which is picked up during certain traffic conditions in said stretch and which releases a short time following a predetermined change in those conditions, and means rendered effective by each of said relay releases for shifting the said master equipment driving connection at the relay location from a first to an opposed contact point of said master coding device whereby to interchange the "on" and the "off" periods of the said master code energy that said driven equipment supplies and thereby disrupt any vacant section coincidence of said special code and master energy pulses that may have prevented those master energy pulses from earlier reaching said opposite section end and there restoring said feed back apparatus to its normal condition of vacant section operation.

7. In combination, a stretch of railway track, a track section included in said stretch, master equipment at a given end of said section operated by either a front or a back master coding contact over a driving connection therewith and effective to supply the section rails with master code energy in the form of recurring "on" period pulses that are separated by "off" period intervals, feed back apparatus at the opposite end of said section driven by the there receiving pulses of said master code energy and operable during and only during said master pulse reception further to supply the section rails with feed back energy in the form of pulses that recur in step with the "off" periods of the received master code, supplemental equipment also at said opposite section end which is operable only when said feed back apparatus is maintained inactive by failure of said master energy to reach the equip- 50

ment location and which then supplies the section rails with special code energy in the form of recurring pulses that have no regular time coincidence with the aforesaid master code "off" periods, a relay at said given section end which delayedly responds to predetermined changes in the traffic conditions of said stretch, and means rendered effective by each of said relay responses for shifting the said driving connection for said master equipment from said back master coding contact to said front master coding contact whereby to interchange said master code "on" and "off" periods and thereby assure restoration of said feed back apparatus to its normal condition of vacant section operation.

8. In combination, a stretch of railway track, a track section included in said stretch, master equipment at a given end of said section operated by either a front or a back master coding contact over a driving connection therewith and effective to supply the section rails with master code energy in the form of recurring "on" period pulses that are separated by "off" period intervals, feed back apparatus at the opposite end of said section driven by the there received pulses of said master code energy and operable during and only during said master pulse reception further to supply the section rails with feed back energy in the form of pulses that recur in step with the "off" periods of the received master code, supplemental equipment also at said opposite section end which is operable only when said feed back apparatus is maintained inactive by failure of said master energy to reach the equipment location and which then supplies the section rails with special code energy in the form of recurring pulses that have no regular time coincidence with the aforesaid master code "off" periods, a relay at said given section end which delayedly responds to predetermined changes in the traffic conditions of said stretch, and means rendered effective by each of said relay responses for shifting the said driving connection for said master equipment from said front master coding contact to said back master coding contact whereby to interchange said master code "on" and "off" periods and thereby assure restoration of said feed back apparatus to its normal condition of vacant section operation.

LESLIE R. ALLISON,
